(57) **CLAIM**

We claim the ornamental design for a light, as shown and described.

DESCRIPTION

FIG. 1 is a perspective view of the light;

FIG. 2 is a top view of the light;

FIG. 3 is a bottom view of the light;

FIG. 4 is a front view of the light;

FIG. 5 is a rear view of the light;

FIG. 6 is a left-hand view of the light;

FIG. 7 is a right-hand view of the light; and,

FIG. 8 is another perspective view of the light.

The light is useful for emanating light. The light can be mounted to a wall or ceiling.
